CLAIM

The ornamental design for a pest repellant pole, as shown and described.

DESCRIPTION

FIG. 1 is a front elevational view of a pest repellant pole showing my new design, wherein the rear elevational view is a mirror image thereof.

FIG. 2 is a right side elevational view of FIG. 1, wherein the left side elevational view is a mirror image thereof.

FIG. 3 is a top plan view thereof; and,

FIG. 4 is a bottom plan view thereof.
